ELECTRIC DISCHARGE STARTING CIRCUIT

Richard M. Somers, Orange, N. J., assignor to
 Thomas A. Edison, Incorporated, West Orange,
 N. J., a corporation of New Jersey

Application March 17, 1934, Serial No. 716,038

6 Claims. (Cl. 176—124)

This invention relates to electric discharge devices, and more particularly to those of the gaseous or vapor type with cathodes heated by external means.

5 The invention is particularly directed to the starting of the main discharge in such a device by the generation of a transient of high voltage and its application between elements within the device. Such a starting method is in general well known, but it is an object of this invention to provide improvements therein and apparatus therefor.

10 It is a more specific object of my invention to provide for such a device a starting circuit characterized by extreme simplicity, economy and positiveness of operation.

15 Another specific object of my invention is to provide, in connection with such a device and the circuit customarily employed for operation thereof from an alternating current source, simple, economical and efficient means for applying a transient of high voltage between the cathode and anodes of the device after the cathode has been heated to substantially full emissivity.

20 It is another specific object of my invention to provide, in a similar connection, an improved starting circuit employing a simple form of switch and arranged to function with minimum impairment of the life of the switch contacts.

25 It is still another object of my invention to replace elements frequently employed in starting circuits for discharge devices of the class described with elements customarily provided within the devices for other purposes.

30 Other and allied objects will more fully appear from the following description and the appended claims:

In the description reference is had to the accompanying drawing, of which:

35 Figure 1 is a partly cross-sectional, partly perspective view of a typical discharge device in which the discharge may be started in accordance with my invention;

40 Fig. 2 is a schematic diagram of the device of Fig. 1 with typical operating circuits and a simplified starting circuit therefor as contemplated by my invention; and

45 Fig. 3 is a diagram generally similar to Fig. 2, but illustrating a modification of the starting circuit of that figure and showing in perspective instead of schematically the switch which I prefer to employ in the starting circuit.

The typical discharge device shown in Fig. 1 may be briefly described as a tube 1 having the 50 glass or the envelope 2, the space 2' within the en-

velope having been evacuated of air and containing either a gas, for example neon, or a vapor, for example mercury vapor, or a combination of gases and/or vapors according to the desired discharge characteristics, it being understood that the term "gas" and its derivatives are elsewhere in this specification used to denote any such gas, vapor or combination. Within the space 2' may be seen the cathode 3, which is of the thermionic type, i. e., adapted to be maintained in an emissive condition by external heating means during the operation of the device. In Fig. 1, I have illustrated this cathode as comprising a folded filament which may be coated with suitable oxides or the like to increase its emission. The extremities of the cathode or filament are secured and electrically connected to the outwardly passing wires or leads 3'. At the opposite end of the device from the cathode are seen the anodes 4a and 4b, respectively secured and electrically connected to the outwardly passing wires or leads 4a' and 4b'.

55 In Fig. 1 will be seen a further element 5. This is in slight spaced relationship to the cathode, and is desirably in the form of a ring essentially surrounding the cathode and interposed between it and the nearest portions 2'' of the envelope 2. This element 5 conveniently performs two functions; one is that of a cathode "activating" element or ring, and the other that of a shield or heat diffuser whereby heat radiated from the cathode is prevented from unduly heating the envelope portions 2''. The second function is of course performed during the operation of the tube, while the first function is performed in the evacuation step in original tube manufacture. It will be understood that in that step the cathode is heated (as by the battery 21 illustrated in Figure 1) and the ring 5 meanwhile maintained at a potential highly positive with respect to the cathode (as by the battery 22 illustrated in Figure 1), this procedure serving in well known manner to activate the cathode by bringing to the surface of its coating a layer of highly emissive material. The activating ring 5 may, for example, be supported and electrically connected to the U-shaped wire 5'', and this in turn to the outwardly passing wire or lead 5'.

60 Reference is now invited to Fig. 2, wherein there appear schematically the envelope 2, the cathode 3, the anodes 4a and 4b, the activating ring 5 and the leads 3', 4a', 4b' and 5' of the tube 1. There will further be seen the transformer 6, shown by way of illustration as an auto-transformer, having primary terminals 6p 65

adapted for connection to the alternating current source through primary switch 9. The cathode heating means is shown in Fig. 2 as the separate secondary winding 7 forming part of the transformer 6 and being connected to the leads 3'. The anode 4a is connected through the ballast resistance or lamp 8a to the extreme transformer secondary terminal 6a; the anode 4b is connected through the ballast resistance or lamp 8b to the extreme transformer secondary terminal 6b; and the cathode is connected to the central transformer secondary terminal 6c through the inductance coil 10.

In the operation of the tube the voltage from the transformer secondary will obviously render the anodes alternately positive with respect to the cathode; the main discharge is therefore intended to comprise a series of alternate discharges between the two respective anodes and the cathode. While the voltage from the transformer on either anode does not rise to a high enough value to start one of the alternate discharges in the first instance, each such discharge succeeding the first starts readily if the period of the preceding one be slightly lengthened, and the accompanying ionization of the gas thereby slightly prolonged. This period lengthening function is performed by the choke or inductance coil 10; this coil also, together with the ballast resistances or lamps 8a and 8b, serves to limit the average values of the alternate discharges. The circuit structure and operation as thus far described will be recognized as conventional.

To start the main discharge in a system of the type described, it is common practice to generate a transient current of relatively high voltage and to apply this between the anodes and the cathode, thereby producing a transient discharge within the tube which by ionizing the gas permits the normal voltage from the transformer terminals to continue the discharge. It further is common practice to delay the generation of this transient, after current is first supplied to the system, for a definite time interval, so that the cathode shall have had time to overcome its thermal inertia and to reach approximately normal operating temperature in response to the operation of its external heating means, e. g., secondary 7. This is usually essential, for if the transient be sooner applied between anodes and cathode a discharge may occur therebetween which will be sustained by virtue of ionic bombardment of the cathode, with attendant de-structure spot heating of the latter.

To generate the transient it is common practice to pass a current through the main discharge period-lengthening inductance, e. g., choke 10 above-mentioned—and abruptly to break this current; thereupon the desired transient appears across the inductance, and by virtue of the circuit position of the latter is automatically applied between anodes and cathode. To effect the desired delay of transient generation, it is common to employ in the circuit passing the just mentioned current through the inductance, i. e., in the starting circuit, a delay switch adapted to close at a predetermined time interval after current is first supplied to the system. To obtain the most desirable phase or polarity characteristics of the transient, which is more effective to the extent that it renders the anodes positive with respect to the cathode, it is customary to restrict to a single one the direction of the current passed through the starting circuit. In systems operated from alternating cur-

rent sources this is frequently accomplished by the use of a full-wave rectifier connected in the starting circuit externally to the tube.

I have found that the full-wave external rectifier may be replaced with the half-wave rectifier inherently provided within the tube by the cathode 3 and the activating ring 5 above-mentioned. The operation of the starting circuit with this arrangement is hereinafter described; the circuit itself, however, together with its features of simplicity, is best described as the connection of a single tap 6d on the auto-transformer through the delay switch 13 and the circuit-breaking switch 12 to the activating ring 5.

The delay switch, by way of example, is shown as comprising a resistance element 13', and a contact arm 13'' responsive to the temperature of the element 13' and adapted to short circuit that element, i. e., to close the delay switch, upon the attainment by the element of a predetermined temperature. The circuit-breaking switch 12 comprises a spring arm 12' carrying the armature 12" and the contact 12a, the arm being biased normally to press the contact 12a against a stationary contact 12b, i. e., to maintain the circuit-breaking switch closed. The armature 12" is positioned in the field of attraction of the core 10' of the choke 10 and is adapted to be moved toward the core 10' and thus to open the switch when the attraction of the core 10' exceeds a certain minimum. The arm 12' is biased at least sufficiently to provide normally a satisfactory contact pressure between the contacts 12a and 12b; at the same time the mass of the arm 12' and the armature 12" are kept reasonably low. Consequently the switch 12 is characterized by rapid response to attractions of the core 10' for the armature 12".

In simple terms the operation of the system may be outlined as follows: Upon the closing of the primary switch 9 heating of the cathode 3 is initiated and the terminals 6a and 6b and the tap 6d are invested with alternating potential differences from the center-tap 6c. As soon as the cathode has been slightly heated a discharge occurs every alternate half cycle from the activating ring 5 to the cathode. The magnitude of this discharge is at first limited by two factors: the then sub-normal emissivity of the cathode, and the resistance of the element 13'. The first of these limitations gradually disappears as the cathode attains normal operating temperature; the second is, of course, independent of the cathode temperature and provides a safeguard against spot heating of the cathode which might tend to be produced, under certain possible voltage conditions, as a result of the occurrence of this ring-cathode discharge prior to full heating of the cathode. The second limitation also prevents the current through the choke 10 and hence the attraction of the core 10' for the armature 12" from becoming sufficient to open the switch 12. The temperature of the element 13' at which it will be short-circuited by the arm 13'' is preferably that temperature which it will have attained by virtue of the current accompanying the ring-cathode discharge, when the cathode has been heated to substantially full emissivity. When this temperature has been attained by the element 13' the delay switch 13 will be closed and the second of the two mentioned limitations removed. Either thereupon, or in the next of the alternate half-cycles during which the ring-cathode discharge takes place (according to the instant in the cycle at which the delay switch 75

closes), this discharge and the current through the choke will rise to relatively high values. The high current through the choke will cause the core 10' to attract the armature 12' and thus to open the circuit-breaking switch 12. This breaks the starting circuit and the flow of current through the choke, causing the generation of the desired transient. The immediately ensuing main discharge causes the passage of sufficient current through the choke to maintain open the switch 12 and hence the entire starting circuit.

The generated transient is required to ionize the gas within the tube, and must therefore not only be of high voltage but must comprise appreciable energy. In general in typical cases, if a current having a peak amplitude of the order of the minimum operating current through the choke be passed through the starting circuit and interrupted when reasonably near its peak value, a transient of ample voltage and energy will be generated. It will be obvious that, by virtue of the far closer spacing of the activating ring to the cathode than of anodes to cathode, sufficient current will be passed in the starting circuit upon closing of the delay switch if there be applied on the activating ring only a minor fraction of the voltage applied to either anode of the tube. Likewise by virtue of the close spacing of the activating ring to the cathode a voltage not greatly in excess of the ionization potential of the gas in the tube will be sufficient to start a ring, cathode discharge each alternate half cycle, after the cathode has become slightly emissive. In practice I therefore employ a relatively low voltage between the tap 6d and the center-tap 6c, preferably positioning the tap 6d as close to 6c as is found by test to result in dependable starting at supply voltages slightly below the lowest expected to be encountered in use. Preferably with any position of tap 6d the bias of the spring arm 12' is maintained at a sufficient value to insure that the switch 12 will open only when the current through the starting circuit is in a peak or near-peak portion of its cycle.

By employing a half-wave rectifier, together with a rapidly acting circuit-breaking switch of simple design actuated only in response to near-peak current values, I am able to secure with a simplified system wholly dependable operation, wherein the main discharge is invariably started upon the first opening of the switch and without a series of ineffective switch openings tending to impair the life of the switch contacts. It is possible that the dependability of the arrangement is enhanced by the fact that the limitation of the instant of circuit breaking to one of near-peak current is also a limitation of that instant to a particular portion of the cycle of voltage on the main anodes. Further, by utilizing in the half-wave rectifier an element or elements necessarily provided within the tube for other purposes, I am enabled to secure a high degree of simplicity and economy. It is further possible that the restriction of the periods of starting circuit current flow resulting from the gaseous discharge nature of the rectifier and the small voltage applied thereacross is a factor which, in addition to the adjustment of switch 12, serves to place the period of possible circuit breaking at a position in the cycle of main anode voltage favorable to the starting of the tube.

Since one of the original limitations of the ring-cathode discharge, i. e., the sub-normal emissivity of the cathode, is a gradually diminishing one and depends directly on the cathode

emissivity, it is possible to utilize this discharge as a measure of the cathode emissivity, and to arrange the starting circuit to break upon the attainment by this discharge of a predetermined magnitude. A circuit for such action is shown as Fig. 3. Therein there is eliminated the delay switch 13, and consequently there disappears the limitation of this preliminary discharge provided while the cathode is sub-normally emissive by the resistance element 13' of Figure 2. It is therefore particularly desirable that every other available safeguard be utilized to minimize tendencies of the preliminary discharge to cause uneven heating of the cathode.

I am aware that a circuit of this last described general character has been proposed, in which opposite alternating voltages have been applied respectively to two auxiliary electrodes adjacent the cathode, the combined discharge from these electrodes to the cathode being employed as a measure of the cathode emissivity and as a control of the circuit-breaking device. In the proposed circuit, however, choke and circuit-breaking device were each required to be in a circuit position similar with respect to the two auxiliary electrodes, while of course remaining subject to the requirement that the choke only be disposed in the path of main discharge current flow. This necessitated the expense and complication of a separate transformer winding for supplying the requisite potentials to these electrodes.

In my simplified circuit as illustrated in Fig. 3, I again employ a rapidly acting circuit-breaking switch 12 (in this figure illustrated in perspective by way of alternative showing), and a simple half-wave rectifier formed within the tube by the activating ring 5 and the cathode 3. I thus avoid the complication and expense of the separate transformer winding and reduce the elements and connections of the circuit to a very simple basis. It is further thought that tendencies of the preliminary discharge to heat the cathode unevenly may be reduced, particularly by virtue of the intermittent nature of the preliminary discharge. It is more particularly desirable in this circuit than in that of Fig. 2, however, that the voltage applied to the activating ring 5, i. e., between the taps 6d and 6c, be kept as low as possible, the bias of the arm 12' of the switch 12 being made just low enough to permit opening of the switch by the attraction of the core 10' produced at an instant of peak ring-cathode discharge when the cathode is substantially fully emissive. The voltage in question must obviously somewhat exceed the ionization potential of the gas; but rather than largely to exceed this potential in the adjustment of the circuit to provide dependably sufficient transient energy for starting any given tube, I prefer if necessary to increase the efficacy of the transient generation by the appropriate introduction of capacity into the starting circuit. Such use of capacity is itself well understood; I have illustrated the same by the condenser 28 connected across the choke 10. It is to be noted that such a capacity may, if desired, be employed in the circuit of Fig. 2, having been dottedly illustrated therein.

While I regard the use of the cathode activating ring in particular for an element of the rectifier as a feature of my invention, it is not intended to limit all aspects of the invention by this feature, it being obvious that another element adjacent the cathode might be employed in obtaining the other beneficial advantages of my invention. Likewise as to other features, I do not in-

tend that the invention be limited by the precise details of the embodiments shown and described, but rather that it be gauged in scope by the following claims.

5. I claim:

1. The combination with an electric gaseous discharge device having a thermionic cathode and an anode, cathode heating means therefor, a source of current connected between said cathode and said anode, and a choke interposed between said cathode and said source: of an electrode adjacent said cathode and forming therewith a rectifier, and a starting circuit for said device adapted to generate across said choke a high-voltage transient, said circuit serially comprising said choke, said rectifier, a circuit-breaking switch having a movable portion of relatively low mass substantially instantaneously responsive to current of predetermined value traversing said circuit, current limiting means operative until said cathode is substantially fully heated, and a source of alternating voltage of value to pass through said circuit when said limiting means is inoperative an intermittent current of peak amplitude only slightly exceeding said predetermined value.
10. and said anode, and a choke interposed between said cathode and said source: of an electrode adjacent said cathode and forming therewith a rectifier, and a starting circuit adapted to generate across said choke a high-voltage transient, said circuit serially comprising said rectifier, said choke, a source of relatively low alternating voltage, and a circuit-breaking switch having a movable portion of relatively low mass, substantially instantaneously responsive to current traversing said circuit, and biased against response to substantially less than the peak values of current traversing said circuit when said cathode is substantially fully emissive.
15. The combination with an electric gaseous discharge device having a thermionic cathode and an anode, cathode heating means therefor, a source of current connected between said cathode and said anode, and a choke interposed between said cathode and said source: of an electrode adjacent said cathode and forming therewith a rectifier, and a starting circuit adapted to generate across said choke a high-voltage transient, said circuit serially comprising said rectifier, said choke, a source of relatively low alternating voltage, and a circuit-breaking switch having a movable portion of relatively low mass, substantially instantaneously responsive to current traversing said circuit, and biased against response to substantially less than the peak values of current traversing said circuit when said cathode is substantially fully emissive.
20. The combination as claimed in claim 4, wherein said electrode is an electrode substantially surrounding said cathode and forming an activating ring therefor during evacuation of said device.
25. The combination as claimed in claim 2, wherein said electrode is an electrode substantially surrounding said cathode and forming an activating ring therefor during evacuation of said device.
30. The combination with an electric gaseous discharge device having a thermionic cathode and two anodes, cathode heating means therefor, a transformer winding adapted for alternating current energization and connected between said anodes, and a choke connecting a central point on said winding to said cathode: of an electrode adjacent said cathode and forming therewith a rectifier, and a starting circuit adapted to generate across said choke a high-voltage transient, said circuit serially comprising said choke, said rectifier, a circuit-breaking switch having a movable portion of relatively low mass substantially instantaneously responsive to current of a predetermined value traversing said circuit, current limiting means operative until said cathode is substantially fully heated, and a single portion of said winding terminating at said central point
35. and two anodes, cathode heating means therefor, a transformer winding adapted for alternating current energization and connected between said anodes, and a choke connecting a central point on said winding to said cathode: of an electrode adjacent said cathode and forming therewith a rectifier, and a starting circuit adapted to generate across said choke a high-voltage transient, said circuit serially comprising said rectifier, said choke, a portion of said winding terminating at said central point and of relatively low voltage, and a circuit-breaking switch having a movable portion of relatively low mass, substantially instantaneously responsive to current traversing said circuit, and biased against response to substantially less than the peak values of current traversing said circuit when said cathode is substantially fully emissive.
40. and two anodes, cathode heating means therefor, a transformer winding adapted for alternating current energization and connected between said anodes, and a choke connecting a central point on said winding to said cathode: of an electrode adjacent said cathode and forming therewith a rectifier, and a starting circuit adapted to generate across said choke a high-voltage transient, said circuit serially comprising said choke, said rectifier, a circuit-breaking switch having a movable portion of relatively low mass substantially instantaneously responsive to current traversing said circuit, and biased against response to substantially less than the peak values of current traversing said circuit when said cathode is substantially fully emissive.
45. and two anodes, cathode heating means therefor, a transformer winding adapted for alternating current energization and connected between said anodes, and a choke connecting a central point on said winding to said cathode: of an electrode adjacent said cathode and forming therewith a rectifier, and a starting circuit adapted to generate across said choke a high-voltage transient, said circuit serially comprising said rectifier, said choke, a portion of said winding terminating at said central point and of relatively low voltage, and a circuit-breaking switch having a movable portion of relatively low mass, substantially instantaneously responsive to current traversing said circuit, and biased against response to substantially less than the peak values of current traversing said circuit when said cathode is substantially fully emissive.
